ELECTRIC SWITCH OPERATING MECHANISM

Filed Nov. 26, 1929

Inventor:
William K. Rankin,
by Charles T. Muller
Attorney.

UNITED STATES PATENT OFFICE

WILLIAM K. RANKIN, OF LANDSDOWNE, PENNSYLVANIA, ASSIGNOR TO GENERAL ELECTRIC COMPANY, A CORPORATION OF NEW YORK

ELECTRIC SWITCH OPERATING MECHANISM

Application filed November 26, 1929. Serial No. 409,983.

My invention relates to hydraulic operating mechanism, and more particularly to operating mechanism for circuit breakers having large interrupting capacities wherein the 5 operating means for closing the breaker must overcome repellent forces during closing movement thereof.

In circuit breakers of comparatively large size and interrupting capacity it is desirable 10 that the movable contact structure of the switch be closed at a substantially uniform or constant speed, i. e. that the applied closing force shall be positive and effective to overcome opposing forces, as repellent magnetic 15 or other forces, tending to slow up closure of the switch. If the speed of closing is too high, severe mechanical stresses may be set up in the apparatus due to the impact at closing, and if the speed is too low objectionable 20 and harmful arcing may occur between the contacts before they are actually engaged. Furthermore, if the application of power for closing the switch is ineffective to overcome the aforesaid repellent forces, the switch may 25 not only remain open, but arcing between the contacts may, as in the case of oil switches for example, cause destruction of the switch.

It is a principal object of my invention to 30 provide an improved electric switch operating mechanism which shall be reliable and positive in operation and simple and rugged in construction.

It is a further object of my invention to 35 provide hydraulic operating means for a circuit breaker of large interrupting capacity arranged so that a switch actuating member may be moved towards its closed circuit position at a substantially constant or uniform speed by fluid pressure notwithstanding the 40 existence or variations in magnitude of forces opposing said movement.

It is a further object of my invention to 45 provide hydraulic operating means for effecting closure of switch mechanism wherein the kinetic energy of rotation of a flywheel is effective to cause a substantially constant or uniform discharge of fluid for moving at a substantially constant or uniform rate an operating member coacting with said mechanism.

My invention will be more fully set forth in the following description referring to the accompanying drawing, and the features of novelty which characterize my invention will be pointed out with particularity in the 55 claims annexed to and forming a part of this specification.

Referring to the drawing, the single figure thereof illustrates an elevational view, partly in section, of a hydraulic operating 60 mechanism for a circuit breaker system.

A tank or fluid reservoir 1 is provided containing a suitable hydraulic medium 2 such as oil, for example. Disposed within the reservoir is a structure 3 for defining fluid passages and for serving as mounting and guiding means for elements acting upon or acted upon by the fluid traversing said passages. The structure 3 forms a main passage 4, at one end of which is disposed a source of fluid pressure or pump of suitable character, as a gear pump comprising a driving gear 5 and a driven gear (not shown) meshed therewith for rotation within a pump casing, in communication with the fluid in the main part 75 of the reservoir. The gear pump may be of the usual well known type wherein the gear teeth pick up the liquid and carry it around in the spaces between the teeth, the pump casing forming therewith a fluid-tight joint. 80 The teeth of the two gears meshing at the center prevent any fluid being carried between them, hence a steady stream of fluid will be forced by the outer gear teeth through the casing and into the passage 4. An essential characteristic of the pump is that it shall be capable of discharging fluid at a rate corresponding to its operating speed. That is, if the speed of the pump is maintained constant the rate of fluid discharge 90 from the pump is likewise constant. At the opposite end of passage 4 there is disposed a valve 6 adapted to seat at 7 for preventing flow of the fluid from the passage into the main part of the reservoir through the ports 95 8. An operating member, comprising a piston 9 and a piston rod 9', is mounted for reciprocal movement within a cylindrical casting 10, which is in open communication at its lower end with the passage 4. The cylindri- 100

cal casing 10 is provided with the exhaust ports or openings 11 in communication with the reservoir for bypassing the fluid acting upon the piston 9 when the lower end thereof has uncovered the exhaust ports.

When the valve 6 is closed actuation of the pump 5 serves to force fluid from the main part of the reservoir into the passage 4, now closed at its opposite end, thereby exerting fluid pressure on the piston 9 tending to force it upwardly until the exhaust ports 11 have been uncovered.

The operating member may serve to actuate suitable mechanism, as for example circuit breaker mechanism used for switches of the oil break type, through a switch actuating member 12. In circuit breakers of the above described character it is desirable that the closing operation be effected with sufficient force to insure closing at a substantially constant or uniform speed. Due, however, to the fact that there are often repellent forces set up by the magnetic forces of the current against which the switch is to be closed, and moreover since these currents in the case of short circuit or overload may vary in magnitude within a wide range, it will be apparent that considerable difficulty may be experienced in effecting closing of the circuit breaker at a substantially constant or uniform speed in the event that provision is not made for overcoming these resisting forces.

The hydraulic operating member 9 and the switch actuating member 12 may be interconnected in any suitable manner to provide the usual trip free action in case of predetermined overload or short circuit, and in the present instance the interconnecting means comprises a bell crank 13 pivotally mounted as at 13' to a frame structure 14 secured to or mounted upon the reservoir 1. One arm of the bell crank 13 is connected as at 15 to the switch actuating member 12 and the other arm is connected as at 16 to one end of a toggle 17. The center or thrust-receiving portion of the toggle 18 is adapted to be engaged by the upper end of the piston rod 9', the other end of the toggle being connected as at 19 to a link 20 pivoted at its opposite end to a stationary lug or support 21. For the purpose of maintaining the pivot 19 of the toggle stationary so that upward movement of the piston rod 9' may extend the toggle to rotate the bell crank 13 in a counter clockwise direction thereby effecting closing movement of the switch actuating member 12, there is provided a latching member 22 pivoted at one end to the frame 14 and having a hook portion 23 at its opposite or free end for engaging the pivot 19 forming a part of the link 20 for restraining it from clockwise movement. It will be apparent, therefore, that disengagement of the latch from the pivot 19 of the toggle permits the link 20 to move in a clockwise direction thereby allowing im-

mediate collapse of the toggle and return of the bell crank and the switch actuating member to their original positions as illustrated. In other words, the latch 22 permits what is known as trip-free action, and to accomplish this end the usual tripping magnet 24 is adapted, when energized a predetermined extent, to engage one arm of a bell crank 25 pivoted as at 26 to the frame 14, and rotate it in a clockwise direction. This movement lifts the link 27, which is connected to the other arm of the bell crank 25 and to the latch 22, to cause counter clockwise movement of the latch 22 sufficiently to disengage it from the toggle.

As previously stated, it is desirable that the hydraulic operating member be acted upon by sufficient force to cause closing of the switch actuating member at a substantially constant speed. To this end the rotatable element of the pump 5 is operated by a shaft 28 driven by suitable motive means, as a motor 29, the driving shaft 28 having fixed thereon a comparatively large and massive rotatable member, as a flywheel 30. Or, the rotor of the motor itself, if of the rotating field type, may comprise the rotatable mass. The motor 29 may be energized from any suitable source of supply 31, and may be controlled by a manually operated switch 32 and a limit switch 33 connected to any suitable part of the switch actuating mechanism, as the bell crank 13 and insulated therefrom as at 33'. When the bell crank 13 is in the open circuit position switch 33 is closed, and when the bell crank has moved to substantially the closed circuit position, the limit switch 33 is opened, thereupon de-energizing the motor 29 and pump 5.

In order that the initial starting movement of the operating member 9 shall be attended by sufficient fluid pressure, the valve 6 is not closed until the motor 29 has come up to predetermined or normal speed thereby enabling the gear pump to deliver fluid at its full rated capacity. For this purpose the valve 6 is adapted to be closed by an electromagnet 35 coacting with a magnetizable core 36 secured to the valve stem 37. The valve 6 is normally biased towards its open position, as illustrated, by suitable means as a spring 38 seated at its upper end against the cover of the reservoir, and bearing at its lower end against a collar 39 secured to the valve stem. Energization of the electromagnet 35 serves to close the valve 6, and de-energization of the electromagnet permits the spring 38 to return the valve to its open position when the piston 9 has reached the end of the stroke and the fluid pressure is reduced by the opening of the ports 11. Energization and deenergization of the electromagnet may be automatically controlled by a centrifugal switch device 40 secured in any suitable manner to the rotating structure of the motor

29. Or, a manually operable switch 40' may be placed in series with the centrifugal switch thereby placing the electromagnet 35 partly under the control of the operator, as where 5 the operation of the main breaker should be in accordance with the indication of a synchroscope. In the present instance the centrifugal switch comprises a pair of flyball contacts 41 mounted upon a portion of the 10 rotor shaft and normally biased towards each other by a spring or other suitable means. Rotation of the rotor shaft serves to force the free ends of the flyball contacts outwardly towards a collector ring 42 connected to a 15 stationary terminal 43. The other terminal 44 may be connected to the flyball contacts through a slip ring 45. Accordingly, rotation of the motor at a predetermined or normal speed is effective to close the circuit 20 through the centrifugal switch, thereupon partially completing the circuit so that the closing switch 40' in series may be operated at the proper time to complete the circuit, 25 energizing the electromagnet 35 from the source 31 and closing the valve 6.

The operation of the mechanism and associated system may be briefly described as follows:

Assuming the parts of the mechanism to 30 be in the positions illustrated, and that it is desired to close the circuit breaker, switch 32 is first closed, causing energization of the motor 29 and pump. Due to the fact that the 35 actual circuit closing operation is effected within a comparatively short time, the operator may readily hold the switch 32 closed until the operation is complete. Or, by closing the switch 32 a relay may be energized for maintaining the motor circuit closed. 40 Initial actuation of the gear pump serves simply to force fluid through the passage 4 back into the main port of the reservoir through the open valve 6 and ports 8. That is, the application of fluid pressure to the 45 piston is delayed while the pump is discharging fluid at a rate less than normal. As the motor attains its normal speed and the pump is discharging fluid at full capacity into the 50 passage 4, the valve 6 may be closed through the centrifugal switch 40 so that the effect of the fluid pressure within the passage 4, which rapidly increases due to the fact that the 55 valve 6 is now closed and the pump discharging a substantially non-compressible fluid into the passage 4, causes the piston 9 to move upwardly at a rate corresponding to the rate of fluid discharged by the pump. When the closing operation is controlled by the 60 centrifugal switch 40 without the additional control switch 40' in series therewith, the system is applicable to feeder circuits.

In the event that the switch actuating mechanism is acting against large repellent forces, any tendency on the part of the piston 9 to slow up is counteracted by the effect of the

large amount of stored energy in the flywheel 80 tending to maintain operation of the pump at constant speed and thereby maintain a constant rate of discharge therefrom. As the piston 9 is lifted to uncover the exhaust ports 70 11, at which point the switch actuating mechanism has been moved to the circuit closing position, the fluid is by-passed into the reservoir and causes no further movement of the piston. As previously described, the motor 29 is deenergized by the limit switch 33 when the toggle 17 has been straightened to close the switch, and in the event that abnormal circuit conditions are present in the circuit 75 to be controlled, the tripping magnet 24 serves to disconnect the hydraulic operating member from the switch actuating member and to permit immediate opening of the circuit breaker.

It shall be understood that my invention is not limited to the specific arrangement and details of construction in the embodiment illustrated and that various changes and modifications will occur to those skilled in the art without departing from the spirit of my invention.

What I claim as new and desire to secure by Letters Patent of the United States is:

1. A circuit controlling system comprising 95 a switch actuating member, a fluid operated member operatively connected with said switch actuating member, a pump for effecting movement of said fluid operated member to circuit closing position at a rate corresponding to the rate of fluid discharged from the pump, a flywheel for maintaining the speed of said pump substantially constant notwithstanding appreciable forces tending to resist closure of said switch actuating member and motive means deenergized upon closing movement of said switch actuating member for actuating said flywheel.

2. A circuit controlling system comprising 100 a switch actuating member, a fluid operated member, means operatively connecting said members, a pump for effecting discharge of fluid so as to cause movement of the fluid operated member and circuit closing movement of the switch actuating member, a flywheel 105 operatively connected to said pump for maintaining discharge of fluid therefrom at a substantially uniform rate, thereby effecting closing movement of the switch actuating member at a substantially constant or uniform rate notwithstanding forces opposing such movement, and means delaying the application of fluid pressure to said fluid operated member until said pump attains normal speed of operation.

3. A circuit controlling system comprising 115 a switch actuating member, a piston operatively connected therewith, a collapsible connection between said piston and switch actuating member, a pump for discharging fluid 120 at a rate corresponding to the speed of the

- pump for effecting circuit closing movement of the piston, means causing opening movement of said switch actuating member through said collapsible connection during switch closing movement of said piston, motive means for driving said pump, and a flywheel operatively connected to said motive means and pump for maintaining the rate of fluid discharge from the pump substantially constant notwithstanding forces opposing movement of the switch actuating member.
4. A circuit controlling system comprising in combination a switch actuating member, a fluid operated member, toggle structure operatively connecting said members for transmitting closing movement to the switch actuating member, a pump for discharging fluid to cause movement of the fluid operated member, a flywheel operatively connected to said pump for maintaining the rate of fluid discharge therefrom substantially constant, the rate of movement of the fluid operated member corresponding to said rate of fluid discharge, and means operable to effect collapse of said toggle structure during closing movement of the switch actuating member thereby permitting immediate reverse movement of the switch actuating member to open position.
5. A circuit controlling system comprising in combination a switch actuating member, a piston operatively connected with said member, a piston operatively connected with said member, a fluid pump for discharging fluid to cause movement of the piston, the rate of movement of the piston in a switch closing direction corresponding to the rate of fluid discharge from the pump, a flywheel operatively connected to said pump maintaining the rate of fluid discharge therefrom substantially constant and closing the switch against repellent forces, a fluid reservoir in which said pump is immersed, a valve disposed within said reservoir in communication with the discharge of the pump, and electromagnetic means controlling said valve for delaying application of fluid pressure to the piston until the pump is discharging fluid at a predetermined rate, said electromagnetic means energized in response to predetermined speed of said pump.
6. A circuit controlling system comprising in combination a switch actuating member, a piston operatively connected with said member, a fluid pump for discharging fluid to cause positive and substantially uniform movement of the piston, and speed responsive means for delaying application of fluid pressure to the piston until the pump is discharging fluid at a predetermined rate.

In witness whereof I have hereunto set my hand this 21st day of November, 1929.

WILLIAM K. RANKIN.
